(57) **CLAIM**

The ornamental design for a combined bed frame and night stand support, as shown and described.

DESCRIPTION

FIG. 1 is a bottom, front perspective view of a combined bed frame leg and night stand support, showing my new design;

FIG. 2 is a top, front perspective view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a top, front perspective view of a combined bed frame leg and night stand support, shown within a first environment of use;

FIG. 10 is a top, rear perspective view thereof;

FIG. 11 is a top, front perspective view of a combined bed frame leg and night stand support, shown in within a second environment of use; and,

FIG. 12 is a top, rear perspective view thereof.

In FIGS. 1-8, the broken lines depict portions of the article that form no part of the claimed design. In FIGS. 9-12, the broken lines depict environmental subject matter that forms no part of the claimed design.

1 Claim, 8 Drawing Sheets
